PACKAGE FOR TOBACCO PRODUCTS
John Staley, Richmond, Va., assignor to Philip Morris
Incorporated, New York, N.Y., a corporation of
Virginia

Filed Dec. 11, 1964, Ser. No. 417,756
6 Claims. (Cl. 229—87)

This invention relates to an improved package for tobacco products and the like and to a method for making the same. More particularly, the present invention relates to an improved cigarette package and method of making the same.

The invention relates most particularly to containers which are made up of a plurality of layers of material, one of said layers being a layer of material, such as aluminum foil, which is substantially impervious to the passage therethrough of water vapor and another of said layers being a fibrous or hydrophilic material, such as paper, which readily picks up moisture from its surrounding environment.

While paper can provide the necessary stiffness and "feel" for a tobacco product package, it obviously does not have the barrier properties of such materials as aluminum or tin foil. On the other hand, aluminum or tin foil, alone, while providing a good moisture barrier, do not have sufficient stiffness in the thicknesses which are economically feasible for packaging operations.

A laminate or its equivalent made of a water-impervious material, such as aluminum foil or the like, and a hydrophilic material, such as paper or the like, provides one of the most economical and most desirable materials for use in the packaging of tobacco products. Thus, a common type of package for tobacco products, and particularly cigarettes, is a package which is made with a laminate which comprises paper and aluminum foil held together by a suitable adhesive and coated on one or both sides, when desired, with a thermoplastic coating. Such laminated packages, which are presently being used commercially in the cigarette industry, are generally folded without being heat-sealed. While it might appear that such a package would, due to the presence of the aluminum foil, form an effective moisture barrier to prevent undue loss or gain of moisture from the cigarettes contained therein, this has not been found to be true. Such packages have been found to be inadequate to maintain cigarettes at the proper degree of moisture for any substantial period of time.

Even when such a laminated package is sealed along its edges by means of heating the thermoplastic coating to a sufficient degree to melt it and permit it to harden to form a seal along the edges of the package, they still fail to form an effective moisture barrier and commercial cigarette packages do not have their edges sealed.

In an attempt to overcome the problem of undesirable moisture loss or gain, when a paper-foil laminate is employed as the packaging material, a separate moisture barrier has commonly been employed with such laminated packages.

The major moisture barrier now in use in the tobacco industry for packaged cigarettes is the cellophane overwrap. This overwrap is actually a separate package which is employed over the laminated package. However, the barrier properties of cellophane are not adequate for properly maintaining the original moisture and oxygen in the contents of the package. Over a period of time, substantial amounts of the water vapor, oxygen and flavorful aromatic vapors can leak through both the inner laminate package and the outer cellophane package.

Coatings made of water impermeable materials, such as wax, have been found to be of some help in increasing

2

the water vapor barrier properties of the package, but solvent action which occurs during sealing operations often removes the coating and exposes the hydrophilic cellophane layer.

5 The present invention overcomes the disadvantages of the prior art and provides an improved package wherein the water vapor transmission rate (WVTR) of the package is greatly reduced and the moisture content of the package product is substantially retained over long periods of time. In addition, the present invention provides a package wherein the loss of volatile materials and flavors from the tobacco product are greatly reduced. The present invention also furnishes a means for controlling the diffusion rate of oxygen into the package whereby spoilage due to the action of anaerobic bacteria can be prevented.

I have discovered that, in packages containing fibrous layers, the fibrous layers function as "wicks" to conduct moisture vapor and other vapors or gases from the inside of the package to the outside or vice versa.

10 No matter how many layers are involved in a laminated material when one of the layers is a hydrophilic or fibrous material, such as paper, the fibrous material provides a wicking effect, conducting moisture either in or out of the package, even though only the edges of the fibrous material are exposed to both the interior and the exterior of the package.

15 In accordance with the present invention, an improved package element is provided comprising a plurality of layers, including at least one fibrous or hydrophilic layer and at least one water-impervious layer, said plurality of layers being folded and joined by means of a plurality of seams to form a package having an interior atmosphere, said package having no fibrous layers which connect the 20 interior atmosphere of the package element with the atmosphere which is exterior to the package element.

25 Briefly, the package element of the present invention can be made by folding under one surface of each seam or joining, so that there is always water vapor impervious 30 layer-to-water vapor impervious layer contact along each seam of the package.

35 The water vapor impervious layer-to-water vapor impervious layer contact, for example, foil-to-foil contact, along each seam, may be on either the inside or the 40 outside of the package element. Furthermore, the package element may be constructed of a plurality of distinct and unjoined layers or may be constructed of a laminate or composite of layers which are joined together by adhesives or resins and coated by waxes, resins and 45 the like.

50 Furthermore, the package element may be employed in conjunction with other packaging elements, such as a cellophane overwrap; a combination of a paper overwrap, 55 which may be suitably printed in color with a brand name and other suitable printed matter, and an outermost cellophane overwrap; an outer cardboard box or an outer plastic case or box.

50 The present invention is particularly applicable to cigarette packages and is equally effective with single component packs, wherein a laminate of paper and aluminum foil forms the entire wrap; with "soft packs," wherein a paper wrap and a cellophane outer wrap are employed with a laminate of paper and foil; with cardboard boxes or plastic cases containing a laminate of foil and paper, and with many other packaging applications.

60 While the invention is particularly applicable to cigarette packages, it is equally effective for use in tobacco pouches and containers for other materials. It may 65 also be employed in conjunction with outer cellophane wrappers, fliptop boxes, plastic cases and the like.

An outstanding advantage of the present invention resides in the fact that with a few simple additional folds in the blank, a tobacco package can be made which is outstandingly superior to any package which has heretofore been made. Thus, with a minimum of additional adjustment and change in packaging equipment, conventional packaging materials can be employed to much greater advantage to provide packages which result in benefits heretofore unachievable with the materials which are employed. Furthermore, the package can be opened in a conventional manner and the only distinction between the appearance and function of the present package from that of conventional cigarette packages is the fact that the flaps are double folded to provide foil-to-foil or similar impervious surface-to-impervious surface contact at all edges and to ensure that no hydrophilic materials are exposed to both the interior and exterior of the package either on their surface or along their edges.

While the package element can be sealed along all its edges, a particularly preferred form of the present invention resides in a package element for tobacco products and the like which not only prevents any significant amount of undesirable transfer of moisture vapor in or out of the package element and which prevents any significant loss of desirable flavors and aromas, but which also permits the passage of oxygen to the interior of the package element. I accomplish this by leaving at least a portion of one foil-to-foil or similar seam of the package element, after it has been formed into the shape of a container, unsealed but by so folding one of the edges of said seam that the resulting free passage or adhesiveless closure from the interior of the package element to the exterior of the package element is at least 50 times and preferably 100 times as long, in the length or direction going to or from the interior of the package to or from the exterior of the package, as the distance or height between the two water vapor impervious surfaces which form the unsealed seam. The entire package element may be made in this manner, without the use of adhesives. Alternatively, an adhesive can be used intermittently along any or all seams of the package element or all but one or a portion of one of the seams may be sealed. However, there should be at least about one-quarter inch and preferably at least about one inch of seam which has the relationship of height to length described above and which is not held together by adhesive. Such a length of seam can be described as an "adhesiveless closure." All other seams in the package element should have a foil-to-foil or similar contact of at least about $\frac{1}{16}$ th inch and, any seam in the package element which does not have the above-described relationship of height to length, should be sealed with a suitable hydrophobic adhesive.

The adhesiveless closure allows the package to "breathe"; that is, it allows oxygen to diffuse into the pack and carbon dioxide to diffuse out of it. It is well known in the tobacco industry that anaerobic action can cause the formation of undesirable aromas within completely sealed or substantially completely sealed packages, when the interior atmosphere of the package falls below a certain oxygen content. Therefore, control of oxygen content is desirable. The adhesiveless closure of the present invention offers excellent protection against the loss or gain of moisture and still allows the passage of oxygen and carbon dioxide to the interior of the package. The length of the unsealed seam controls the "breathing" and the passage through the seam has essentially zero permeability if, as set forth above, the length of the path in the direction of diffusion is greater than approximately 50 times the width of the gap.

The "wickless" packages of the present invention have been proven to be many times more effective in reducing moisture migration in packaged cigarettes than the standard packages overwrapped with cellophane. And the combination of a "wickless package" with an adhesive-

less closure of the type described above has provided even greater overall advantages.

Thus, packages of the present invention can be employed to provide an opening for the exchange of oxygen and carbon dioxide between the contents of the package and the atmosphere, the exchange taking place without any significant change in the moisture content of tobacco. The invention thereby provides for a package which can be stored for long periods of time without any undesirable moisture changes and without any undesirable changes due to the absence of oxygen in the package.

The present invention overcomes a long standing problem in the art: a package which was stored for a long period of time with a barrier which was sufficient to prevent moisture loss had a resulting depletion of its oxygen content, whereby the tobacco was subject to attack by anaerobic bacteria. If, on the other hand, the package was stored for a long period of time without such a moisture barrier, in order to provide for passage through the package of oxygen, moisture would be lost or, in the event of an atmosphere that was excessively moist, the tobacco would pick up excessive moisture, in short, the moisture content of the tobacco would be changed undesirably. Such problems are eliminated by the present preferred method and process.

Water vapor impervious materials which may be employed in accordance with the present invention include aluminum foil, tin foil, lead foil, polyethylene, polypropylene, wax and the like. Calendered plasticized vinyl resin sheets may also be employed. A vinyl resin sheet can comprise polymerized vinyl chloride or copolymers of vinyl chloride with vinyl esters, vinyl acetate and vinylidene chloride. These materials may be employed as sheets or as coatings and, when employed as sheets, may be employed as lamina, adhered to other lamina by means of suitable adhesives, or may be used with other lamina without being adhered thereto.

Fibrous or hydrophilic materials which may be employed in accordance with the present invention include such materials as paper, for example, glassine, kraft paper, sulfite paper and the like, thin cardboard and similar materials.

The water vapor impervious material and the fibrous material, when both are in sheet form, may be joined together by a suitable adhesive which may be any of the well-known types that may or may not be applied with a solvent or, on the other hand, may include a thermoplastic type of adhesive. Various adhesives are known for bonding paper to metal, for example, casein glues and silicate cements.

The outer surface of either or both layers of the resulting laminate may then be coated either completely or partially, along the areas to be joined together, with a thermoplastic material or may be bonded to a thermoplastic sheet, said thermoplastic coating or sheet being free from tackiness at normal atmospheric temperatures and possessing such thermoplastic cohesive properties that it can be used to selectively bond the edges of the package together due to the application of heat and pressure.

The specific nature of the thermoplastic sheets or coatings which may be employed may vary somewhat in compositions, although such material should, in any event, have the physical characteristics mentioned above. Suitable materials include polyethylene, polypropylene, rubber hydrochloride (commercially available as "Pliofilm"), chlorinated rubber (commercially known as "Pliolite"), alkyd resins, phenol formaldehyde resins, vinyl acetate polymers, polyvinyl chloride homopolymers and copolymers, vinylidene chloride polymers, for example, "Saran," cellulose derivatives as cellulose esters and cellulose ethers, for example, cellulose acetate, when properly plasticized with selected plasticizers in suitable amounts, copolymers of butadiene and styrene, polystyrenes, nitrocellulose coatings properly plasticized with selected plasticizers so as to be suitably thermoplastic, inert protein

polymers when properly formulated and plasticized, and other generally similar compositions of thermoplastic materials which are free from tackiness at normal atmospheric temperatures but have such thermoplastic cohesive properties that they may be selectively bonded together permanently or superficially by the application of heat and pressure.

The resulting laminate may then be employed with the water vapor impervious material on either the inside or the outside of the package, so long as the blank from which the laminate is made is folded and sealed in accordance with my invention.

The use of a thermoplastic outer layer or coating is preferred, since it can be readily employed to heat seal the edges of the package. However, when no thermoplastic materials is used as an outer coating or surface layer, a water impervious resin or adhesive may be applied to the edges of the package to seal the edges in accordance with the present teachings.

In the preferred embodiment of the invention, wherein an adhesiveless closure is employed, i.e., wherein at least one seam is left partially unsealed and wherein all seams may be unsealed, a coating of thermoplastic materials, such as polyvinyl acetate, on the water vapor impervious layer, such as foil, which is preferably relatively thin, for example, from 0.05 to 0.8 mil in thickness, does not change the results which are obtained from a foil-to-foil or similar relationship, provided the coating itself is not hydrophilic, i.e., does not serve as a wick, and provided the proper ratio of length to width of the opening, as set forth earlier in this specification, is maintained. Such coated foil-to-coated foil or similar contact can, for the purposes of this application, be considered foil-to-foil contact.

In the case where there has been heat sealing of two coated foil-to-coated foil surfaces, by means of a thermoplastic coating, it can be considered that there is essentially a foil-to-foil contact established through the heat seal.

For a fuller understanding of the nature and objects of this invention, reference should be had to the accompanying drawings, in which:

FIG. 1 is a plan view of a blank from which the package element of the present invention can be made.

FIG. 2 is a perspective view of the package element;

FIG. 3 is a front view of the package element;

FIG. 4 is a sectional view of the package of FIG. 3, taken along the line 4-4 except that the thickness of the lamina is shown exaggerated; and

FIG. 5 is an enlargement of an upper portion of FIG. 4.

As shown in FIGS. 1-5, and particularly in FIG. 1, laminated blank 1 which comprises an inner or lower lamina 1a made of fibrous or hydrophilic material, such as paper, and an outer or upper lamina 1b, made of a vapor barrier, such as aluminum foil, which is bonded to the inner lamina by a suitable adhesive is rectangular in shape. The upper lamina may be coated completely on its face with a thermoplastic resin, such as polyvinyl acetate. Blank 1 comprises longitudinal score lines 2-7, lateral score lines 8-10 and 10' and angular score lines 11-16 and 11'-16'. Score lines 4, 8, 5 and 9 define the front panel B. Score lines 3, 8, 4 and 9 and 5, 8, 6 and 9 define, respectively, the side panels A and C. Score lines 2, 8, 3 and 9 and 6, 8, 7 and 9 define, respectively, the back panel section D and the back panel section E. The top folds of the package are formed by that portion of the blank bounded by edges 20, 21' and 22 and score line 8. The bottom folds of the package are formed by that portion of the blank bounded by edges 20, 21 and 22 and score line 9.

To form the novel container of the present invention from blank 1, side panel A is folded back along score line 4 until it is at an angle of 90° from the plane of front panel B. Side panel C is similarly folded back,

along score line 5 until it is at an angle of 90° with the plane of front panel B. Back panel section D, which is defined by score lines 2, 8, 3 and 9 and is folded back, along score line 3 to form an angle of 90° with the plane of side panel A. Back panel section E, which is formed by score lines 6, 8, 7 and 9, is folded along score line 6 to form an angle of 90° with the plane of side panel C. Flap F, which is formed by score line 7 and edges 21', 22 and 21, is folded inwardly through an angle of 180° along score line 7 and is then positioned so that its upper surface, in this case aluminum foil, then forms a lower surface which is defined by score lines 7, 8 and 9 and edge 22, is positioned over edge area G which is bounded by score lines 8, 2 and 9 and edge 20 which is adjacent rear panel section D. In this manner, a foil-to-foil seam is made which can be sealed by heat sealing the thermoplastic coating, if used, or by applying a suitable adhesive and sealing the two seams together. Preferably, where a water impervious seal is desired, the foil is completely coated with a polyvinyl acetate coating and is heat sealed at the seam to melt the polyvinyl acetate and permit it to cool to form the seal along said seam.

Panel H, which is bounded by score lines 3, 9 and 4 and edge 21 is folded inwardly to form an angle of 90° with panel A along score line 9. When panel H is folded inwardly, it holds triangularly shaped panel J, which is bounded by score lines 3 and 11 and edge 21 and triangularly shaped panel K, which is bounded by score lines 4 and 12 and edge 21 outwardly so that they fold, respectively, along score lines 11 and 13 at an angle of 180° with, respectively, panel P which is bounded by score lines 2, 9 and 11 and edge 21 and panel Q which is bounded by score lines 9, 13, 10 and 12. When panel L, which is bounded by score lines 5, 9 and 6 and edge 21, is folded inwardly, it holds triangularly shaped panel N, which is bounded by score lines 6 and 14 and edge 21, and triangularly shaped panel M, which is bounded by score lines 5 and 13 and edge 21, outwardly so that they fold, respectively, along score lines 14 and 13 at an angle of 180° with, respectively, panel R, which is bounded by score lines 9, 7 and 14 and edge 21 and panel Q, which is bounded by score lines 9, 13, 10 and 12.

The flap formed by panels P and R, which are backed, respectively, by triangularly shaped panels J and N, is then folded along the score line 9 inwardly at an angle of 90° from the plane of back sections D and E, respectively, whereby foil-to-foil contact between panels J and H and panels N and L is made. Panel Q is then folded over at its outer edge along score line 10 to form a flap S, which is bounded by score lines 10, 12 and 13 and edge 21 to form an angle of 180° with the foil surface of panel Q. Panel Q is then folded at an angle of 90° along score line 9 to form an angle of 90° with front panel B, whereby flap S is in foil-to-foil contact with panels P and R. Triangularly shaped panels J and N are heat sealed, respectively, to panels H and L, panels K and M are heat sealed, respectively, to portions of panels H and P and portions of panels R and L and flap S is heat sealed to both panel P and panel R. The resulting series of heat seals forms a water impermeable end to the package just as the heat sealing of edge formed between flap F and edge area G is heat sealed to form a water impervious side seam.

Panel H', which is bounded by score lines 3', 8' and 4' and edge 21' is folded inwardly to form an angle of 90° with panel A' along score line 8'. When panel H' is folded inwardly, it holds triangularly shaped panel J', which is bounded by score lines 3' and 11' and edge 21' and triangularly shaped panel K', which is bounded by score lines 4' and 12' and edge 21' outwardly so that they fold, respectively, along score lines 11' and 13' at an angle of 180° with, respectively, panel P' which is bounded by score lines 2', 8' and 11' and edge 21' and

panel Q' which is bounded by score lines 8', 13', 10' and 12'. When panel L', which is bounded by score lines 5', 8' and 6' and edge 21', is folded inwardly, it holds triangularly shaped panel N', which is bounded by score lines 6' and 14' and edge 21', and triangularly shaped panel M', which is bounded by score lines 5' and 13' and edge 21', outwardly so that they fold, respectively, along score lines 14' and 13' at an angle of 180° with, respectively, panel R', which is bounded by score lines 8', 7' and 14' and edge 21' and panel Q', which is bounded by score lines 8', 13', 10' and 12'.

The flap formed by panels P' and R' which are backed, respectively, by triangularly shaped panels J' and N', is then folded along the score line 8' inwardly at an angle of 90° from the plane of back sections D' and E', respectively, whereby foil-to-foil contact between panels J' and H' and panels N' and L' is made. Panel Q' is then folded over at its outer edge along score line 10' to form a flap S', which is bounded by score lines 10', 12' and 13' and edge 21' to form an angle of 180° with the foil surface of panel Q'. Panel Q' is then folded at an angle of 90° along score line 8' to form an angle of 90° with front panel B', whereby flap S' is in foil-to-foil contact with panels P' and R'. Triangularly shaped panels J' and N' may be heat sealed, respectively, to panels H' and L', panels K' and M' are heat sealed, respectively, to portions of panels H' and P' and portions of panels R' and L' and flap S' may be heat sealed both to panel P' and panel R'. The resulting series of heat seals, if employed, forms a water impermeable top end to the package just as the heat sealing of edge formed between flap F' and edge area G' is heat sealed to form a water impervious side seam and the bottom of the package was heat sealed.

In the preferred form of this invention, however, panels H', J', K', L', M', P' and R' are folded, as indicated, but are not heat sealed, whereby they form an adhesiveless barrier. In such event, each foil-to-foil contact must be such that the length to width ratio of the opening is at least 50. This is more fully illustrated in FIGS. 4 and 5.

By referring to FIG. 5, wherein portions of panels P' and Q' are shown, the relationship between the length, y, of the space between the foil-to-foil surfaces and the width, x, of the space between the foil-to-foil surfaces can readily been seen.

This ratio of y:x should be at least 50:1 and may be 1000:1 or even higher.

Were all the seams to be sealed, as described earlier, the ratio of y:x should be at least 10:1 and may be 1000:1 or even higher.

The invention is further illustrated by the following examples.

Example 1

A paper-laminated-to-foil wrapper for a single-component cigarette pack was prepared by attaching aluminum foil (0.00035 inch thickness) coated continuously with polyvinyl acetate to 60-pound bond paper with a conventional adhesive (casein). The resulting wrapper or laminate was cut to the proper size to form a blank. The blank was then scored along fold lines in a manner similar to that shown in FIG. 1 that would give foil-to-foil contact and insure that no edges of the paper would be exposed to the outside when the blank is folded to form a cigarette package.

The scored laminate was folded about the cigarettes in a manner similar to that described with regard to the drawing and each fold was heat sealed with a hand sealer heated to a temperature of about 275°-300° F., whereby the polyvinyl acetate coating was melted and served to seal the folds together. The package was then enclosed with a cellophane overwrap. Similarly, another package was prepared with no cellophane overwrap. A standard soft pack (with standard folds which leave paper edges exposed) was used as a control.

The test packs and controls were conditioned for about 24 hours, then stored for six days, and at the end of the storage period, their water vapor transmission rates were determined. The cigarettes were analyzed either by the oven method or the gas chromatographic method for their initial moisture content. The cigarette packs were weighed and then placed in storage cabinets maintained under hot-wet conditions (90° F., 85% R.H.) and under hot-dry conditions (110° F., 15% R.H.). Ten samples of each of the two test packs and the control were used for each storage condition. The packs were conditioned in the storage cabinets overnight (16 to 24 hours) and then weighed to obtain their basic weights. At the end of six days, the packs were weighed to obtain the final weights. The cigarettes in the packs were analyzed for their final moisture content. The WVTR was calculated as follows:

Rate of moisture loss=

$$\frac{\text{Basic pack wt. (grams)} - \text{final pack wt. (grams)}}{(6 \text{ days}) \times (20 \text{ cigs./pack} \times \text{av. tobacco wt./cigt., grams})} = \text{percent/day}$$

Rate of moisture gain=

$$\frac{\text{Final pack wt. (grams)} - \text{basic pack wt. (grams)}}{(6 \text{ days}) \times (20 \text{ cigs./pack} \times \text{av. tobacco wt./cigt., grams})} = \text{percent/day}$$

Results of the calculations are given below:

	Av. Moisture Loss/Day, Percent	Av. Moisture Gain/Day, Percent
Control, Cellophane.....	0.438	0.444
Pack, No Cellophane.....	0.218	0.082
Pack, Cellophane.....	0.098	0.078

As can be seen from the data above, the wickless pack is 2-4 times more effective than the standard pack for preventing moisture migration. As a part of the same test, actual changes in the moisture content were determined. The original moisture content of the cigarettes in all three types of pack was 12.61%, calculated on an as-is basis (nondried). The packs were stored for six days in hot-dry and hot-wet conditions—110° F. and 15% relative humidity (R.H.) and 90° F., 85% R.H. At the end of the storage period (termed "seven-day" storage because the day of conditioning was counted), the percent of tobacco moisture change was calculated by subtracting the percent moisture of the original tobacco from the percent moisture after storage or vice versa. The results are given below:

	7-Day Storage	
	Moisture Loss, Percent	Moisture Gain, Percent
Control, Cellophane.....	2.81	2.54
Single Component, No Cellophane.....	1.76	0.44
Single Component, Cellophane.....	0.51	0.44

The heat sealed wickless package without a cellophane overwrap was not as effective against moisture migration as the one with a cellophane overwrap but both of the wickless packs were significantly superior over the control as water vapor barriers.

Example 2

Paper-laminated-to-foil liners were prepared as described in Example 1, from 45-pound and 20-pound bond paper and aluminum foil (0.00035 inch thickness). The 20-pound bond laminate was used to enclose a bundle of cigarettes to go into a flip-top box; the 45-pound bond laminate was used to enclose a bundle of cigarettes which

was overwrapped with a printed paper label and a cellophane overwrap (a soft pack). Likewise, the 20-pound bond/foil was used as the container of cigarettes to go inside a plastic pack.

Each of these packages and their controls were submitted to storage under hot-wet and hot-dry conditions for six days and their water vapor transmission rates were calculated according to the formulae given in Example 1. The results are shown below:

	Average Moisture Loss/Day, Percent	Average Moisture Gain/Day, Percent
Flip-Top Box/20 pound Bond/Foil Perforated/Cellophane	0.384	0.315
Control (Standard Flip-Top Box)	0.622	0.458
Flip-Top Box/20 pound Bond/Foil Non Perforated Cellophane	0.209	0.262
Control (Standard Flip-Top Box)	0.622	0.458
Soft Pack 45 pound Bond/Foil Cellophane	0.141	0.095
Control (Standard Soft Pack)	0.400	0.386
Plastic Pack/20 pound Bond/Foil/Cellophane	0.128	0.056
Control (Plastic Pack/Cellophane)	0.240	0.185
Plastic Pack/20 pound Bond/Foil/No Cellophane	0.161	0.070
Control (Plastic Pack/Cellophane)	0.240	0.185

Example 3

Paper-laminated-to-foil wrappers which had been continuously coated with polyvinyl acetate were scored as described in Example 1. The top fold was prepared to insure that the length of the fold would be 50 times the width of the gap when folding was completed. The blanks were then folded into cases and all folds, except the top folds, were heat sealed. Cigarettes were inserted, and the top was spot sealed to hold the top fold close to the package but still leave a passageway through which oxygen and carbon dioxide could diffuse. Similar packs were completely heat sealed and used as a control.

The original moisture content of the tobacco in the test and control packs was determined.

By using a rubber seal to completely obviate the possibility of an ingress of atmosphere into the pack, a syringe was inserted into the test and control packs, and the gases contained in the pack were pulled out. The original composition and amounts of these gases were determined mass spectrophotometrically. Packs which matched these packs were stored for two months and again the gases in the test and control packs were determined. It was found that the test pack and control originally contained oxygen and carbon dioxide in the same percentage in which they occur in the atmosphere. After the two-month storage period, the oxygen and carbon dioxide content of the unsealed pack remained essentially the same as the percentage in which they occur in atmosphere. In the sealed pack, the oxygen content had decreased and the carbon dioxide had increased. The moisture content of both packs was measured and found to be virtually the same. The unsealed pack had "breathed"; that is, by diffusion carbon dioxide had escaped from the pack and oxygen had entered it. At the same time, the lack of a complete seal had little effect on moisture migration.

The two packs of cigarettes were submitted for subjective evaluation of pack aroma. A difference in pack aroma was detected by the panel, and a preference for the pack aroma of the unsealed pack was expressed.

I claim:

1. A container for cigarettes formed from a substantially rectangular blank comprised of a plurality of layers, at least one of which is a hydrophylic layer and at least one of which is a water-impervious layer, said blank being folded to form a tubular body of substantially rectangular cross section having four side walls, two opposed ends of the blank being overlapped to form a seam extending longitudinally of said body, said body having

portions of opposed side walls adjacent both ends thereof folded inwardly substantially perpendicular to said side wall providing end walls for the container, each folded portion having a segment thereof overlapping a segment of at least one other folded portion, the overlapping segments of the respective folded portions forming seams in the corresponding container end walls, the overlapping segments forming each end wall seam and said longitudinal seam comprising edges of said blank which have been infolded to provide a water-impervious layer to water-impervious layer contact substantially along the entire length of the corresponding seams, the overlapping segments forming each seam providing passages through the container from the interior to the exterior thereof, each of said passages having a length which is at least 50 times greater than the spacing between the overlapping segments forming said seams.

2. A container for cigarettes formed from a substantially rectangular blank comprised of a plurality of layers, at least one of which is hydrophylic layer and at least one of which is a water-impervious layer, said blank being folded to form a tubular body of substantially rectangular cross section having four side walls, two opposed ends of the blank being overlapped to form a seam extending longitudinally of said body, said body having portions of opposed side walls adjacent both ends thereof folded inwardly substantially perpendicular to said side walls providing end walls for the container, each folded portion having a segment thereof overlapping a segment of at least one other folded portion, the overlapping segments of the respective folded portions forming seams in the corresponding container end walls, the overlapping segments forming each end wall seam and said longitudinal seam comprising edges of said blank which have been infolded to provide a water-impervious layer to water-impervious layer contact substantially along the entire length of the corresponding seams, the overlapping segments forming each seam providing passages through the container from the interior to the exterior thereof, each of said passages having a length which is at least 50 times greater than the spacing between the overlapping segments forming said seams, said seams permitting gas flow therethrough.

3. A container for cigarettes formed from a substantially rectangular blank comprised of a plurality of layers, at least one of which is a hydrophylic layer and at least one of which is a water-impervious layer, said blank being folded to form a tubular body of substantially rectangular cross section having four side walls, two opposed ends of the blank being overlapped to form a seam extending longitudinally of said body, said body having portions of opposed side walls adjacent both ends thereof folded inwardly substantially perpendicular to said side walls providing end walls for the container, each folded portion having a segment thereof overlapping a segment of at least one other folded portion, the overlapping segments of the respective folded portions forming seams in the corresponding container end walls, the overlapping segments forming each end wall seam and said longitudinal seam comprising edges of said blank which have been infolded to provide a water-impervious layer to water-impervious layer contact substantially along the entire length of the corresponding seams, the overlapping segments forming each seam providing passages through the container from the interior to the exterior thereof, the passage along a portion of at least one seam having a length which is at least 50 times greater than the spacing between the overlapping segments forming said one seam, the passages along the remaining seams having lengths at least 10 times greater than the spacing between the overlapping segments forming said seams, said remaining seams being filled with adhesive.

4. A container for cigarettes formed from a substantially rectangular blank comprised of a plurality of layers, at least one of which is a hydrophylic layer and at

least one of which is a water-impervious layer, said blank being folded to form a tubular body of substantially rectangular cross section having four side walls, two opposed ends of the blank being overlapped to form a seam extending longitudinally of said body, said body having portions of opposed side walls adjacent both ends thereof folded inwardly substantially perpendicular to said side walls providing end walls for the container, each folded portion having a segment thereof overlapping a segment of at least one other folded portion, the overlapping segments of the respective folded portions forming seams in the corresponding container end walls, the overlapping segments forming each end wall seam and said longitudinal seam comprising edges of said blank which have been infolded to provide a water-impervious layer to water-impervious layer contact substantially along the entire length of the corresponding seams, the overlapping segments forming each seam providing passages, the passage along a portion of at least one seam having a length which is at least 50 times greater than the spacing between the overlapping segments forming said one seam, the passages along the remaining seams having lengths at least 10 times greater than the spacing between the overlapping segments forming said seams, said remaining seams being filled with adhesive, said one seam permitting gas flow therethrough.

5. A container for cigarettes formed from a substantially rectangular blank comprised of a plurality of layers, at least one of which is a hydrophylic layer and at least one of which is a water-impervious layer, said blank being folded to form a tubular body of substantially rectangular cross section having four side walls, two opposed ends of the blank being overlapped to form a seam extending longitudinally of said body, said body having portions of opposed side walls adjacent both ends thereof folded inwardly substantially perpendicular to said side walls providing end walls for the container, each folded portion having a segment thereof overlapping a segment of at least one other folded portion, the overlapping seg-

ments of the respective folded portions forming seams in the corresponding container end walls, the overlapping segments forming each end wall seam and said longitudinal seam comprising edges of said blank which have been infolded to provide a water-impervious layer to water-impervious layer contact substantially along the entire length of the corresponding seams, the overlapping segments forming each seam providing passages through the container from the interior to the exterior thereof, each of said passages having a length which is at least 100 times greater than the spacing between the overlapping segments forming said seams.

6. In a container for cigarettes which is formed by folding around the cigarettes a substantially flat blank comprised of a plurality of layers, at least one of which is a hydrophylic layer and at least one of which is a water-impervious layer with the blank having at least two opposed ends which are overlapped, the overlapping segments of the blank forming a seam on the container, the improvement wherein the overlapping segments comprise edge portions of the blank which have been infolded to provide water-impervious layer to water-impervious layer contact substantially along the entire length of the seam, the overlapping segments forming said seam providing a passage through the container from the interior to the exterior thereof, said passage having a length which is at least 50 times greater than the spacing between said overlapping segments.
